UNITED STATES PATENT OFFICE.

FELIX T. WHITTED, OF WHEELEY, ARKANSAS.

BUCKLE.

No. 809,874.

Specification of Letters Patent.

Patented Jan. 9, 1906.

Application filed May 26, 1905. Serial No. 262,484.

To all whom it may concern:

Be it known that I, FELIX T. WHITTED, a citizen of the United States, residing at Wheetley, in the county of St. Francis and State of Arkansas, have invented certain new and useful Improvements in Buckles, of which the following is a specification.

This invention relates to buckles, and more particularly to that type which employ a pivoted stud to engage the perforations in the strap.

It has for its object to produce a device of this character which can be easily and quickly adjusted to any desired position, which will be effective in operation, and which is at the same time simple and durable in construction.

For a full description of the invention and the merits thereof and also to acquire a knowledge of the details of construction of the means for effecting the result reference is to be had to the following description and accompanying drawings, in which—

Figure 1 is a perspective view of a buckle, showing it applied. Fig. 2 is a longitudinal sectional view showing the buckle in a locked position. Fig. 3 is a detail perspective view of the separate parts.

Corresponding and like parts are referred to in the following description and indicated in all the views of the drawings by the same reference characters.

The frame of the buckle comprises the side pieces 1, which have their ends bent upward at 2 and connected by cross-bars 3. Lugs 4 extend upward from intermediate points on the side pieces 1 and are provided at suitable places with openings 5, which serve as bearings for the thumb-lever 6. A stud 7 is attached to the thumb-lever and is adapted to engage the openings in the strap when in normal position. An intermediate cross-bar 8 serves the double function of forcing the long

line into engagement with the stud 7 and of serving as an attaching means for the short line 10.

In operation the short line is attached to the intermediate cross-bar 8 and the long line passed between said cross-bar and the thumb-lever when the latter is in a raised or unlocked position. When the buckle has been adjusted to the desired position upon the long line, the thumb-lever 6 is forced down and the stud 5 forced into engagement with one of the openings. It will now be noticed that the harder the long line is pulled the tighter will be the engagement with the thumb-lever. The upturned ends of the side pieces serve to throw the end cross-bars out of a tight engagement with the strap and permit same to be easily slid through the buckle for adjusting purposes.

Having thus described the invention, what is claimed as new is—

A buckle comprising straight side pieces having their opposite ends bent upwardly in a similar manner and connected by cross-bars, said side pieces being provided with upwardly-extending lugs having openings therein, an intermediate cross-bar located adjacent the upwardly-extending lugs, and a thumb-lever pivotally mounted in the openings in the before-mentioned lugs and provided with a stud adapted to engage with the openings in a long line, the intermediate cross-bar performing the double function of holding the long line in engagement with the stud and of serving as an attaching means for a short line.

In testimony whereof I affix my signature in presence of two witnesses.

FELIX T. WHITTED. [L. s.]
